(57) **CLAIM**

The ornamental design for a lunch box with handle, as shown and described.

DESCRIPTION

FIG. 1 is a front perspective view of a lunch box with handle, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a view of the lunch box with handle shown in an open configuration.

The broken lines in the drawings illustrate the portions of the lunch box with handle, which form no part of the claimed design.

1 Claim, 9 Drawing Sheets
